UNITED STATES PATENT OFFICE.

WILLIAM THOMAS HALL, OF WINNIPEG, MANITOBA, CANADA

AUTOMOBILE LOCK.

Application filed May 9, 1921. Serial No. 467,970.

To all whom it may concern:

Be it known that I, WILLIAM THOMAS HALL, of the city of Winnipeg, in the Province of Manitoba, Canada, have invented 5 certain new and useful Improvements in Automobile Locks, of which the following is the specification.

The invention relates to improvements in automobile locks and particularly to a device for locking the steering post against rotation and an object of the invention is to provide a lock which can be easily applied on the various existing types of automobile steering post columns and positively fastened in place and which is arranged so that all the vital parts are not exposed and accordingly not accessible to one attempting to break the lock.

20 A further object is to provide a lock of comparatively few parts which when applied will positively lock the steering post against movement and which is arranged so that it can be easily manipulated by the driver in the locking or unlocking operation.

A further object is to provide a lock which can be manufactured at comparatively small cost, is of good appearance and is light, compact and durable.

30 With the above more important and other minor objects in view which will appear as the description proceeds the invention consists essentially in the arrangement and construction of parts hereinafter more particularly described and later pointed out in the appended claims, reference being had to the accompanying drawing in which:—

Fig. 1 is a perspective view of the lock as it appears in use and in the closed position.

Fig. 2 is a perspective view of the lock with door or gate in the open position.

Fig. 3 is a horizontal sectional view through the lock.

45 Fig. 4 is a vertical sectional view through the lock at 4-4' Fig. 3 and looking inwardly.

In the drawing like characters of reference indicate corresponding parts in the several figures.

1 represents the steering post of an automobile which is rotated in the usual manner by the steering wheel to operate the front wheels. This post is customarily enclosed at the upper end within a stationary column or tube 2. In the present instance the

lower end of the column is shown as secured to a stationary bracket 3 permanently secured to the dash 4. To the column I attach my locking appliance indicated generally by the reference numeral 5, which appliance is now described in detail. 60

6 is the body part of the appliance which is cast to provide a strap like back 7 forming a stationary gripping jaw 8, the gripping face of which is somewhat less than a semi-circle. At the sides the casting is hollow to provide side cavities 9 and 10 and within the cavities and adjoining the stationary jaw I form two seats or shoulders 11 and 12, the inner sides of these shoulders actually terminating the ends of the jaw 8.

Between the extending side portions of the body piece I locate an adjustable member 13 which is also specially cast to provide a movable jaw 14, the gripping face 15 of which is somewhat less than a semi-circle. The movable jaw is formed integral with top and bottom wings 16 and 17 and side lugs 18 and 19, the lugs being adapted to engage or oppose the shoulders 11 and 12, whilst the wings make sliding contact with the top and bottom walls of the cavities 9 and 10. 75 80

In referring to Fig. 4 it will be seen that 85 lapped joints are provided as indicated at 20, such style of joint preventing of one gaining access to the interior of the appliance by a prod or similar tool. When the movable jaw and integral parts are in 90 place the front side of the appliance presents a substantially rectangular open end which is fitted with a closure gate or door 21 pivotally mounted for swinging movement on a pin 22 carried by one of the side 95 portions of the body part 6. A continuous ledge, shoulder or stop 23 is provided for the door to close against, the arrangement being that when the door is closed the outer face lies flush with the front edges of the 100 substantially rectangular entrance opening herein before mentioned and the shoulder 23 prevents one from getting into the interior of the appliance at the door crack such as with a knife, prod or such like other 105 thin tool.

At the left hand end the door is provided with an extension 24 which passes to the rear of a vertically cast web 25, the arrangement being such that should the pin 22 be knocked out that end of the door cannot be pulled outwardly provided the other end is 110

locked. The free or swinging end of the door is fitted with a lock 26 provided with the customary key hole for the reception of the controlling key 27 and with a rotat- 5 ing catch plate 28 adapted in the rotation of the lock barrel to pass in behind a retaining web 29 cast integral with the body part 6. The other details of the lock are not enlarged upon as it is a commercial 10 commodity which I can buy and apply on the door.

From the above arrangement it will be apparent that when the door is closed and the key turned to locking position the catch 15 plate will lock behind the web 29 and lock the door positively closed.

Centrally on the inner side the door is provided with two opposing lugs 30 and 31 which carry a pivot spindle 32, the pivot 20 spindle having the lower end projected beyond the lug and fitted with a finger piece 33. Between the lugs and to the spindle I secure permanently the head of the locking pin 34, which pin is adapted when idle to 25 lie against the inner face of the door and within the cavity 9 and when in use to extend at right angles to the door and pass through registering openings 35 and 36 provided in the jaw 14 and the column 2 and 30 into a receiving hole 37 drilled radially in the post 1. The head of the pin is arranged to engage the door and stop it in a position at right angles to the same when it is turned by the spindle. In this way the operator 35 has no trouble as when the door is say in the open position as shown in Fig. 2 he simply applies a finger on the finger piece 31 and rotates the spindle as far as he can at 40 which time the pin is stopped in a position at right angles to the door.

In order to insure of the quick and easy entrance of the locking pin into the openings 35 and 36 I have provided an internal cross web 38 cast with the jaw 14 and the outer 45 face of this web is inclined gradually so as to guide the pin into the opening as the door is swung closed. The lower wing 17 is slotted as indicated at 39 to receive the spindle in the closed position of the door. 50 The jaw 14 is held adjustably to the body part 6 by adjusting screws 40 and 41 passing through the lugs 18 and 19 and screw threading into the shoulders 11 and 12. The heads of the screws are exposed within the cavities 55 9 and 10 so that when the door is opened they can be easily approached for adjusting purposes.

When a automobile is to be equipped with my invention the steering post and column 60 are drilled to provide the opening 36 and hole 37 to receive the locking pin. The device is then placed on the column by first opening the door, then removing the screws 40 and 41 and afterwards withdrawing the 65 removable jaw. When the body part has

been placed on the column with due regard to the position of the openings 36 and 37 in respect to the locking pin the inserted member 13 is securely fastened in place by tightening up the screws 40 and 41 which effects 70 the gripping of the column positively between the jaws.

I wish here to state that the arrangement provides for a variation in the diameter of the column as the jaws are somewhat less 75 than a semi-circle and the member 13 can be slid out to accommodate a slight increase in the diameter of the column.

Once the device has been securely attached to the column by tightening up the screws 80 as just explained the post can be easily and quickly locked against rotation by closing the door and locking it and at the same time swinging the pin so that it will enter the opening 36 and hole 37 in the post.

During the interval that it is not desired to have the post locked one simply opens the door and turns the pin to lie against the door. He can then lock the door again with the pin in the cavity 9.

I wish to draw particular attention to the fact that I have designed this device to make it what might be termed thief-proof. With the door locked it is impossible for the thief to get into the interior of the device as all 95 exposed cracks are guarded and the door has been arranged so that if the pin 22 be knocked out nothing is gained as that end of the door is still locked against movement in one direction by the extension 24 engaging 100 the web 25 and in the other direction by the engagement of the door with the shoulder 23. I have purposely decreased the diameter of the extending end of the spindle 32 so that under abnormal conditions, as when 105 roughly handled by a thief, it will break off. This however will not give the thief entrance to the interior of the lock as the lower lug 31 closes over the slot 39 and even if it were possible to withdraw the spindle access 110 cannot be had to the locking pin and the said pin cannot move even although the spindle is pulled out.

I might here remark that the door is comparatively thick and it is my intention that 115 in any position of the adjusting member 13 the wings 16 and 17 shall over and underlie the edges of the door.

What I claim as my invention is:—

1. The combination with the steering post 120 and the tubular column receiving the post, the column and post being both provided with openings which can be brought into registration in the turning of the post, of a lock comprising a body member clamped to 125 the column and provided with an opening registering with the opening in the column and having the rear side open to provide a doorway, a pivoted door adapted when closed to close the doorway opening, a lock 130

for the door and a locking pin carried by the door in foldable relation therewith and adapted when extended to pass through the registering openings of the body member 5 and the column and into the opening of the post.

2. The combination with the steering post and the tubular column receiving the post, the column and post being both provided 10 with openings which can be brought into registration in the turning of the post, of a lock comprising a body member clamped to the column and provided with an opening registering with the opening in the column 15 and having the rear side open to provide a doorway, a door adapted to close the doorway opening, a lock carried by the free side of the door and adapted to lock the door closed, a pivoted locking pin carried by the 20 inner side of the door and extending towards the body member and adapted to enter the openings in the body member, column and post and exterior means for manipulating the pin to direct it into the openings in the 25 closing of the door.

3. In an automobile lock, the combination with the steering post and column receiving the same, said post and column being provided with openings which can be brought 30 into registration in the turning of the post, of a two-part body member adjustably clamped to the column and having an opening therein registering with the opening in the column and having the rear side open 35 to provide a door opening, a door pivotally secured to the body member and adapted to close the latter opening, a key lock carried by the swinging side of the door and adapted to lock the door closed, a locking pin pivotally secured to the inner side of the door 40 and designed in the extended position and during the closing of the door to pass into and through the registering openings in the body part, column and post and exteriorly manipulated means for controlling the 45 pin to direct it into the openings in the door closing operation.

4. In an automobile lock, the combination with the steering post and column receiving the same, said post and column being provided with openings which can be brought 50 into registration in the turning of the post, of a two-part body member presenting stationary and adjustable gripping jaws engageable with the front and rear sides of the column and with the adjustable jaw having an opening therein registering with the opening in the column, said body part presenting a rear doorway opening and an 55 interior cavity, adjusting screws housed within the cavity and adjustably attaching the jaws together, a pivoted door adapted 60

in the closed position to close the doorway opening, a key controlled lock carried by the free side of the door and adapted to lock 65 the door closed, a spindle pivotally mounted on the inner side of the door and crossing the same, said spindle extending beyond the body part of the lock in the closed position of the door, a finger piece secured to the extending end of the spindle and a locking pin carried by the spindle, said locking pin being adapted to be directed into the registering openings of the jaw, column and post as the door is closing and by the manipulation 75 of the finger piece.

5. In an automobile lock, a body member having stationary and adjustable column gripping jaws and interiorly recessed and fitted with a doorway opening and an interior ledge within the doorway opening and having one of the jaws provided with a locking opening communicating with the recess, a pivoted door adapted to close the opening and engage the ledge, a key operated lock carried by the free edge of the door for locking the same closed, a pivoted spindle carried by the inner side of the door and crossing the same and provided at the extended end with a finger grip and a pin secured to the spindle, said pin lying normally against the door in the unlocked position thereof and being adapted to be turned and manipulated by the finger piece to direct the pin into the locking opening during the 95 closing of the door.

6. In an automobile lock, a clamping member presenting an adjustable and a stationary jaw and providing an interior cavity and having a locking opening passing 100 through one of the jaws, a door pivotally attached to the clamping member and adapted to close the entrance to the recess, means for locking the door closed and a locking pin carried by the door in foldable relation 105 therewith and insertable into and through the locking opening in the clamping member.

7. The combination with the steering column and the post of an automobile, said column and post having openings therein adapted to be brought into registration in the turning of the post, of a two-part clamping member attached to the column, a foldable locking pin carried by the clamping member and adapted to enter the registering openings of the post and column and means preventing removal of the locking pin.

Signed at Winnipeg, this 15th day of February, 1921.

WILLIAM THOMAS HALL.
